UNITED STATES PATENT OFFICE.

MARION E. McCLELLAN, OF McCLELLAN, MINNESOTA.

TOE-STRAP FOR SKEES.

1,391,260.

Specification of Letters Patent. Patented Sept. 20, 1921.

Application filed September 8, 1920. Serial No. 408,982.

To all whom it may concern:

Be it known that I, MARION E. McCLELLAN, a citizen of the United States, residing at McClellan, in the county of Koochiching 5 and State of Minnesota, have invented certain new and useful Improvements in Toe-Straps for Skees, of which the following is a specification.

This invention relates to toe-straps for 10 skees and is especially designed to securely hold the foot of the user without providing any obstruction which might retard his progress or cause his equilibrium to be disturbed by contact with adjacent objects.

15 A further object of this invention is to provide a device of this character which although snugly embracing the foot will reduce pressure thereon to a minimum.

The above and other objects of this invention will be in part described and in part 20 understood from the following description of the present preferred embodiment of the invention, taken in connection with the accompanying drawings, wherein;

25 Figure 1, is a perspective view of a toe-strap constructed in accordance with my invention illustrating its application.

Fig. 2, is a cross sectional view of a skee showing my invention applied thereto, the latter being shown in side elevation, and 30

Fig. 3, is a side fragmentary elevational view of a skee embodying my invention illustrating the application of the same.

In the drawings a portion of a skee 4 is 35 provided which may be of any suitable design. The skee is provided in its opposite sides with recesses 5 which preferably taper inwardly toward the center of the skee as shown to advantage in Fig. 2.

40 The device of my invention consists of lugs of identical configuration. Each lug consists of a strand of wire 6, the opposite ends of which are pointed and driven into the recesses 5 at the bottom of the latter.

45 The strands are then bent upwardly and inwardly into engagement with the inner ends of the recesses within the lateral margins of the skee. The vertices of the lugs are bent inwardly as indicated at 7 to provide arcuate inner faces conforming substantially to

the shape of the foot. The sides of the lugs are held together by a bar 8 which is arranged in close proximity to the upper end of the lugs.

55 A strap 9 is passed through the lugs between the upper ends thereof and the bars 8 as shown to advantage in Fig. 2. One end of the strap is equipped with a buckle 10 which co-operates with the opposite end of the strap thereby holding the strap from 60 displacement. It will be observed that the buckle is arranged above the lower run of the strap to prevent contact of said buckle with the foot of the user.

65 It is no doubt obvious from the above that the user of the skee will simply slide his foot between the upstanding lugs 6 pursuant to which the strap is pulled into snug engagement with the top of the foot as illustrated in Fig. 3. By seating the lugs in the 70 recesses 5 projection beyond the lateral margins of the skee will be prevented eliminating the possibility of the lugs coming in contact with adjacent objects. Tapering the recesses 5 permits the lugs to incline inwardly and better conform to the shape of 75 the foot.

It is understood that various changes may be made in the construction of the lugs or the strap which spans the lugs. The above 80 described form simply illustrates the principle of the invention.

What is claimed is:

85 A toe-strap for skees including lugs each of which consists of a strand of wire, the opposite ends of which are pointed and penetrated in the side of the skee, the intermediate portion of said strand being extended upwardly and inwardly toward the longitudinal center of the skee, a bar connecting the sides of the strand and a strap 90 extending from one lug to another and adapted to embrace the foot of the user of the skee.

95 In testimony whereof I affixed my signature in presence of two witnesses.

MARION E. McCLELLAN.

Witnesses:

EDWARD McCLELLAN,
FRANK BALMER.
